UNITED STATES PATENT OFFICE.

FRANKLIN A. SMITH, JR., OF PROVIDENCE, RHODE ISLAND.

METALLIC FASTENING.

SPECIFICATION forming part of Letters Patent No. 296,079, dated April 1, 1884.

Application filed January 17, 1884. (No model.)

To all whom it may concern:

Be it known that I, FRANKLIN A. SMITH, Jr., a citizen of the United States, residing at Providence, in the county of Providence and State of Rhode Island, have invented certain new and useful Improvements in Metallic Fastenings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to an improved metallic fastening which is designed to be used in the place of a common headed tack, but in the present instance is more particularly adapted for use as a fastening for securing buttons to fabric, and of that class for which Letters Patent of the United States were granted me, dated January 2, 1883, No. 269,891; and my present invention is designed as an improvement on the same.

20 Heretofore tack-fastenings have been made of metal cut to a sharp point on different sides, and having a head forced into form by means of heading-dies, making a broad head on all sides of the prong. In the above-mentioned 25 patent a round pin-pointed stem projecting from the interior of a concavo-convex circular disk-head is employed, all of which must necessitate the employment of costly machinery in the manufacture, and when in use as a button-fastening causes a disk of metal on the under surface of material which is liable to tip up when a strain is brought to bear on the button, thus hurting the foot and rendering it objectionable as a shoe-fastening. My present 30 invention is designed to remedy this defect, as but a small amount of metal is employed in the manufacture, the base portion being disposed in such a manner as to present but a small amount of metal on the inner surface of 35 a shoe, and this in such a form as to be practically unobjectionable, and at the same time provide a strong and durable fastening for an eye-shank button.

To this end my invention consists of a base 40 or head portion, from the cut edge of which,

and at right angles thereto, extends a prong which is gradually curved on each side, ending in a sharpened point similar to a lancet form, the whole cut from sheet metal of a uniform thickness at head and point, the metal in the finished fastener being in its normal condition as it existed in the sheet from which it is cut.

45 To more particularly describe my invention, I refer to the drawings, in which Figure 1 is a plan view of the fastener. Figs. 2 and 3 represent opposite views of the fastener attached to buttons in fabric ready for use as a button-fastener. Fig. 4 is a view of sheet metal with a fastener cut out of it.

50 Similar letters refer to similar parts throughout the several views.

Again referring to the drawings, A is a tack or fastener, cut to form out of sheet metal of a uniform thickness, with the metal of the finished article in its normal or unbent condition as it existed in the original sheet, without any bending, swaging, or further manipulation whatever, as shown in view of sheet metal with blank cut out in Fig. 4; and it consists of the base a, from the center of which, on the cut edge thereof, extends at right angles the fastening-prong b, which is preferably cut to a gradual curve not unlike a lancet form, terminating in a central pointed end, c, 60 as shown in Fig. 1. This end is pointed sufficiently to allow it to be readily pressed through fabric when used as a button-fastener, or to readily penetrate any material which it may be used in connection with.

65 As before stated, in the present instance I more particularly design the tack for a button-fastener, in which case the operation of attachment is as follows: The prong b is first pressed through the fabric and button-eye until the 70 cut edge of the base a lies snugly against the under side of the fabric, when a pressure being brought to bear on the end c, the prong b is bent over flatwise of the stock at right angles to the base and re-enters the fabric until the end c reaches the side of the base at its center, when on striking the base, and a further pressure being brought to bear on the prong b, the end c is farther carried down until it reaches the lower edge of the base, the fastener 75

assuming the form of a loop substantially like that shown in Fig. 3, *d*, when the button will be found to be firmly secured to the fabric.

It will be observed that the prong being cut 5 out of sheet metal and bent flatwise of the stock in attaching a button to fabric, will make a much smaller circle or loop around the button-eye than if it were bent edgewise, and the strain, coming in two places in the material 10 against the flat surface of the fastening-prong, offers a greater resistance to any pressure that is brought to bear on it, and also prevents the fastener from turning or twisting around while in the fabric, as is the case with other forms of 15 tack-fasteners, this being an important feature of my invention.

Having described my invention, what I claim as new, and desire to secure by Letters Patent, is—

The herein-described metallic tack or fastener *A*, consisting of the base *a*, having a rounded lower and substantially straight upper edge, from the center of which projects the prong *b*, terminating in point *c*, substantially as shown and described. 20

In testimony whereof I affix my signature in the presence of two witnesses. 25

FRANKLIN A. SMITH, JR.
